(57) **CLAIM**

The ornamental design for a linear recessed lighting fixture, as shown and described.

DESCRIPTION

FIG. 1 illustrates a top perspective view of a linear recessed lighting fixture, according to a first embodiment.

FIG. 2 illustrates a bottom perspective view of the linear recessed lighting fixture, according to the first embodiment.

FIG. 3 illustrates a side view of the linear recessed lighting fixture, according to the first embodiment.

FIG. 4 illustrates an opposite side view of the linear recessed lighting fixture, according to the first embodiment.

FIG. 5 illustrates a front view of the linear recessed lighting fixture, according to the first embodiment.

FIG. 6 illustrates a rear view of the linear recessed lighting fixture, according to the first embodiment.

FIG. 7 illustrates a top-plan view of the linear recessed lighting fixture, according to the first embodiment; and, FIG. 8 illustrates a bottom-plan view of the linear recessed lighting fixture, according to the first embodiment.

Broken lines shown in the drawings represent portions of the linear recessed lighting fixture that form no part of the claimed design.
